(57) **CLAIM**

The ornamental design for the memory card adapter, as shown and described.

DESCRIPTION

FIG. 1 is a top, right isometric view of the invention, on an enlarged scale;

FIG. 2 is a bottom, left isometric view of the same, on an even greater enlarged scale;

FIG. 3 is a front elevational view of the same;

FIG. 4 is a right side elevational view of the same;

FIG. 5 is a left side elevational view of the same;

FIG. 6 is a rear elevational view of the same; and,

FIG. 7 is a bottom plan view of the same.

The broken line drawing in FIGS. 1, 2, 4, 5 and 7 is for illustrative purposes only and forms no part of the claimed design.
